UNITED STATES PATENT OFFICE.

HARRY P. DAVIS, OF HEMPSTEAD, NEW YORK.

TERMINAL CONNECTER.

Application filed October 19, 1921. Serial No. 508,781.

To all whom it may concern:

Be it known that I, HARRY P. DAVIS, a citizen of the United States of America, and resident of Hempstead, Long Island, county of Nassau, New York, have invented certain new and useful Improvements in Terminal Connecters, of which the following is a specification.

This invention relates to certain improvements in terminal connecters and the like; and the nature and objects of the invention will be readily understood by those skilled in the art in the light of the following explanation and detailed description of the accompanying drawings illustrating what I at present believe to be the preferred embodiments or mechanical expressions of my invention from among other forms, arrangements, combinations and constructions within the spirit and scope thereof.

The present invention has particular reference and is particularly applicable to connecters for securing and confining the electrical cable or conductor terminals of electrical systems, of internal combustion motors, to the spark plugs, magnetos and such other electrical apparatus and devices as these systems may include, although the invention is equally applicable and adapted to form the connection between the electrical conductor or cable terminals and the binding posts and such like, of various other types of electrical apparatus and devices.

The electrical apparatus and connections in electrical systems of internal combustion motors are subjected to great vibration and strain, and this is particularly true with respect to the electrical conductors or cables secured to and electrically connecting the spark plugs of internal combustion motors with the various apparatus of the ignition systems. Due to the fact that the spark plugs of such motors are detachably and removably mounted for cleaning, adjustment and replacement, it follows that it is necessary to detachably secure the electrical conductors or cable terminals thereto which connect the plugs with the other apparatus of such systems, in order to permit the ready detachment or disconnecting of these cable terminals from the spark plugs when it is necessary to remove the same. As well known and appreciated by those familiar with internal combustion motors, this requirement for a readily detachable terminal

connection between the electrical conductors or cables and the spark plugs of such motors results in continuous breakage and interruption of the connections because of the great vibration and strain to which they are subjected. The foregoing disadvantages are also present at other points and in other connections where conductor or cable terminals are detachably secured to electrical apparatus and devices and subjected to any vibration, strain or like forces tending to break such connections.

The present invention includes as one of the main objects thereof to overcome and avoid the breakage or interruption of electrical conductor and cable terminal connections through vibration, strains and other forces to which they may be subjected, by the provision of a readily detachable and positive locking conductor or cable terminal which when attached to a binding post or such like element, is securely locked and fastened against detachment by vibration and other forces applied thereto in normal use and operation.

A further object of this invention is to provide a terminal connector which can be quickly and readily attached to and detached from the element to which it is desired to secure the same, and which in attached position will permit movement of the element relative to the connector, as well as movement of the connector with respect to the element, so as to avoid twists and bends in the conductor or cable and permit the connector to move into approximate alignment with the conductor or cable in attached position.

A further object of this invention is to provide an electrical conductor or cable terminal connector which can be readily attached to and detached from a spark plug, binding post or other similar element, and one which in attached position forms a positive electrical contact with and between the element and the conductor or cable on which it is mounted.

A further object of this invention is to provide an improved construction and arrangement for mounting and securing a terminal connector to the terminal or end portion of an electrical conductor or cable and which construction provides a protection for the terminal and affords the means to be grasped by the operator in attaching and

detaching the connector to and from a binding post or the like, as well as providing a protection to the operator against electrical shocks in handling a connector to detach the same.

A further object of this invention is to provide a quickly attachable and detachable connector for securing the terminals of electrical conductors and cables to the binding posts and similar elements of electrical apparatus, and which connector in attached position is securely and positively locked against breakage, jarring loose or detachment through vibration and strains applied thereto, but which may be readily and quickly unlocked and detached by pressure manually applied thereto in a certain manner and direction.

A further object of this invention is to provide a detachable electrical terminal connector which is so formed and constructed as to be applicable to and fit practically all standard types of spark plug, magneto and various other binding posts and like elements of electrical apparatus, and to be interchangeable and practically universal in character in order to overcome the necessity of providing special terminal connectors for each type of apparatus and binding posts or the like, to which they are to be attached.

A still further object of the invention is to provide a connector for securing the terminals of electrical conductors and cables to binding posts and similar elements, which connector is of simple but durable construction, inexpensive to manufacture and of a high efficiency in operation and use.

With the foregoing and other objects and advantages in view, which will be readily understood and appreciated by those skilled in this art, the invention consists in certain novel features in construction, and in formation and arrangement of parts as more fully and particularly set forth and specified hereinafter.

Referring to the accompanying drawings,

Figure 1 is a top plan view of a terminal connector embodying features of the present invention and shown in locked attached position.

Fig. 2 is a top plan view of a terminal connector of the invention in unlocked detached position and prepared for attachment and locking to a spark plug, binding post or similar element.

Fig. 3 is a view in side elevation showing a spark plug with a terminal connector of the invention locked in attached position thereon, the terminal mounting being shown in vertical section.

Fig. 4 is a bottom plan view of a terminal connector of the invention, in closed locked position.

Fig. 5 is a vertical longitudinal section through a terminal connection of the in-

vention in locked and attached position on a spark plug, a portion of the plug being shown in dotted lines.

Fig. 6 is a detail perspective view of one of the movable engaging and locking jaws 70 of the invention.

In the present instance, and purely by way of example, I have illustrated and described the application of the invention to and in use with a spark plug of an internal combustion motor, but it is to be understood that I do not intend or desire to limit the invention to use only in connection with spark plugs, as it is intended and evident that the invention is applicable to use with and attachment to numerous other types of electrical apparatus and devices and to various forms and types of binding posts and the like elements. In the accompanying drawings, as an example of the above application, I show a spark plug 10 of a type well known to those familiar with this art, and provided with the binding post or head 11 having the annular groove 11^a, therearound, and to which binding post the terminal of an electrical conductor or cable can be detachably connected in electrical contact therewith.

The form and embodiment of my invention for detachably connecting the terminal of an electrical conductor or cable to, for example a spark plug, as illustrated in the accompanying drawings, comprises an engaging plate or member 20 provided with extended opening 21 therethrough and toward the forward end portion thereof. This opening 21 decreases in width forwardly toward the outer end of the plate 20 for a purpose appearing hereinafter, and the plate 20 decreases in width forwardly with the front end thereof rounded, in the preferred form, so that the plate 20 substantially conforms in exterior form to the shape of the opening 21, although it is not desired to limit the plate 20 to this particular shape or form. The opposite end of the body portion of the member or plate 20 extends for a distance beyond the opening 21 and has a portion thereof bent or otherwise extended at an angle to the plate thereof to provide the tab 22 for electrically securing the plate 20 to the terminal of an electrical conductor or cable. The bent end portion or tab 22 is provided with a circular aperture 22^a for a purpose pointed out hereinafter. The plate 20 is preferably constructed or formed of spring brass or phosphor bronze to provide a somewhat resilient but very durable plate which will be an extremely good conductor of electricity, although if desired, various other materials containing the suitable properties may be employed.

A pair of similar locking jaws 30 are pivotally mounted on one face of the plate 20 and in closed locking position extend

- across the opening 21 of the plate 20. The jaws 30 are pivotally mounted to the side of the plate 20 opposite that side from which the tab 22 extends, that is the side which for purposes of clearness will be hereafter referred to as the upper side of the plate 20. The jaws 30 are pivotally mounted on the plate by means of the pivots or the like 31 secured through the plate 20 adjacent the inner end of the opening 21 and extend forwardly across the plate and opening 21 to and terminating in line with the forward end edge of the plate 20, as clearly illustrated in the accompanying drawings. In closed, locked position the jaws 30 extend forwardly across and completely cover the upper side of the plate 20 with the outer side edges of the jaws in substantial alignment with the outer edge of the plate (see Figs. 1 and 4) of the drawings, so that in locked position the jaws assume substantially the contour and shape of the plate 20 which they cover forwardly of the pivots 31. The inner adjacent side edges of the jaws 30 are straight and with the jaws 30 in closed position abut or contact in a line extending substantially along the longitudinal center of the plate 20. In order to permit free swinging movement to and from closed, locked position on the pivots 31, the jaws 30 have the pivoted ends thereof cut away and rounded at 30°, as clearly shown in Fig. 2 of the drawings.
- Each pivoted locking jaw 30 is formed with a cut away portion forming a semi-circular opening 32 adjacent the forward end of the jaw and extending from the straight inner edge thereof. These semi-circular openings 32 are formed in the jaws 30 opposite each other respectively, so that when the jaws are in closed locked position the semi-circular openings 32 align to form a circular opening or aperture through the forward end portion of the abutting jaws 30. Further, the position of the openings 32 in the jaws 30, with respect to the opening 21 through the plate 20, is such that the circular opening formed by the closed contacting jaws is directly above and has its forward curved edge in alignment with the forward curved side of the opening 21, so that, the radius of the circle through the circumference of the opening formed through the closed jaws 30 is approximately equal to the radius of the circle of which the curved forward edge of the opening 21 is an arc and the centers of these circles are in alignment to provide the registered opening through the plate 21 and jaws 30, with the latter in closed locking position. The rear edge portion of each opening 32 is bent, pressed or otherwise inclined downwardly to form the inclined portion 32a. With the jaws 30 in closed locked position the inclined portions 32a are adjacent and present a downwardly inclined surface extending around the rearward side of the circular opening formed through the closed jaws 30 by the opposite joined openings 32. The upper surfaces of the downwardly inclined portions 32 may be beveled slightly, or the downwardly inclined surface may be formed by beveling the rear sides of the openings 32 without requiring the bending or pressing of the rear sides, this feature of the invention residing in providing a downwardly inclined surface at the rear portion of the opening through the jaws.
- In order to provide for securely locking the jaws 30 in closed position on and across the engaging plate 20 and the opening 21 therein, each jaw 30 is formed with a downwardly extending projection or lug 33, in the particular example illustrated herewith formed by depressing a portion of the jaw downwardly to extend from the under side thereof, although it is evident that these projections or lugs 33 may be formed in various other ways without departing from the spirit and scope of this invention. The lugs or projections 33 are so positioned from the under side of each jaw that with the jaws 30 in closed position the lugs extend within the opening 21 and engage against the opposite edges thereof, respectively, and lock the jaws 30 in closed position. Due to the resiliency of the plate 20 and the jaws 30 together with a slight play at the pivots, the projections 33 may be forced over and across the opposite sides of the plate 20 to permit the jaws to swing into open unlocked position, and to be swung to closed locked position, with the projections forced across the plate 20 and snapping into the opening 21 to secure the jaws into closed position.
- The mounting for electrically securing and firmly attaching a terminal connector of the invention as described hereinbefore, comprises a screw plug 40 having a central neck or projection 41 extending from one end thereof and a central bore extending through said neck and the plug 40, with the bore enlarged at the end of the plug opposite the projection 41 to provide a substantially conical opening extending through the plug and decreasing in size toward the projection 41. An electrical cable 50 of the usual or any other type, and comprising the usual heavy insulation and central conducting core of wires 51 is inserted in the plug 40 with the insulation thereof cut to conform to the conical portion of the bore through the plug and the wire conducting core 51 extending through the projection 41 and a distance therebeyond. A fibre, hard rubber, or like insulating material sleeve 52 is fitted over the cable 50 and internally screw threaded at one end to receive the

screw plug 40, as shown in Fig. 3, of the drawings.

With the cable terminal provided with the foregoing construction and arrangement 5 of plug 40 and sleeve 52, the terminal connector of the invention is secured and attached to the cable terminal in electrical connection therewith by means of the tab 22 extending from the engaging plate 20 10 of the terminal connector. As pointed out the tab 22 is provided with the aperture 22^a and this aperture 22^a is fitted over the end projection or neck 41 of the screw plug 40 with the tab 22 bearing flatly against the 15 outer end of the plug 40 and sleeve 52 and the engaging plate 20 extending outwardly from the cable terminal and substantially in line with the cable 50. The end of the wire core 51 then extends through the plug 20 40 and aperture 22^a in the tab 20, and is bent or "spilled" against the outer side of the tab 22, being securely and rigidly secured thereagainst by means of solder or the like, as shown at 51^a in Fig. 3 of the 25 drawings.

In the foregoing manner the terminal connector is securely and rigidly fastened to the terminal of an electrical conductor or cable in proper electrical connection therewith, and extending substantially in line with and in continuation of the cable.

In the operation and use of the described embodiment and construction of the invention, to attach the terminal connector to, for 35 example the spark plug of the drawings, the pivoted locking jaws 30 are swung outwardly to the open position as shown in Fig. 2 of the drawings, with the area of the opening 21 through the engaging plate 20 40 unobstructed by the jaws 30. Then, by grasping the insulating sleeve 52, the engaging plate 20 is placed over the binding post or head 11 of the spark plug 10, the post 11 passing and extending through the 45 enlarged rearward portion of the opening 21 of the plate 20. With the terminal connector in the foregoing position, the jaws 30 are swung inwardly toward each other and against the post 11 of the plug which there- 50 by forces the connector outwardly and brings the post into the forward, decreased portion of the opening 21, with the forward portion of the plate 20 within and partially surrounding the groove 11^a in the post 11. 55 As the jaws 30 are swung inwardly to closed position the lugs or projections 33 pass across the plate 20 and spring or snap into the opening 21 against opposite sides thereof when the jaws reach abutting closed position. In closed position of the jaws the 60 opposite semi-circular openings 32^a formed therein receive and fit around the post 11, within the groove 11^a and the jaws thereby completely surround and em- 65 brace the binding post 11 within and con-

fined by the groove 11^a. The terminal connector in attached position is securely connected to and on the binding post 11 of the spark plug 10, first by the projections of lugs 33 extending within and bearing 70 against the sides of the engaging plate opening 21 which prevents opening or spreading of the jaws to release the binding post, and secondly, by the fact that the jaws 30 are confined against movement away from the plate to lift the projections 33 from engagement with the plate 20 to permit swinging of the jaws 30 to open position, by the upper and lower faces of the groove 11^a in which the jaws 30 and plate 20 are confined and which press the jaws against the lower plate 20. In other words, vibrations or strains transversely of the plate 20 and jaws 30 tending to force the same upwardly or downwardly on the post 11, will not cause the projections 33 to release the jaws and permit opening thereof, as forces in such directions cause the plate 20 and jaws 30 to be more firmly pressed or jammed together, as will be readily seen by reference 80 to Fig. 5 of the drawings. Vibration and strains tending to act longitudinally of the connector will not detach or open the same due to the forward end of the plate 20 and to the jaws 30 held against opening by the 85 projections 33 and completely surrounding and confining the binding post to which they are attached thereto. It will be noted that in attached position to and in electrical connection with a binding post, the terminal connector of the invention is free to rotate or swing therearound with the post as an axis, so that all twisting and bending of the conductor or cable to which the connector is mounted and secured is avoided. 90

In order to detach the terminal connector of the invention from a binding post to which it is attached and locked, the insulating sleeve 52 is grasped and pressure is applied longitudinally of the connector to force 100 or push the engaging plate 20 and pivoted jaws 30 mounted thereon toward the binding post. Due to the downwardly inclined portions 32^a at the rear or inner side of the openings 32 of the jaws 30, the post 11 in the present instance, bears thereagainst and they act or perform the function of cam surfaces, so that, the post 11 forces the jaws apart against the resistance of the projections 33 which are forced onto and across the sides of the engaging plate 20. When the jaws have been thus forced clear of the opening 21 to a position such as shown in Fig. 2, the engaging plate may be detached or lifted from engagement with the binding 110 post.

The construction and mounting of the insulating sleeve 52 protects the cable or conductor terminal against weather conditions and particularly moisture, so that, the pres- 115 120 125 130

ent terminal connector is of particular advantage in use with marine and stationary motors exposed to the elements. Further, the provision of the insulating sleeve 52 permits removal of the connector from spark plugs and like electrical apparatus and devices with the motor running or with current passing through the cable, as the hand of the operator in removing the connector 10 is protected thereby against all danger of shocks. The manner of securing the terminal of a conductor or cable into electrical contact with the terminal connector by means of the plug 40 and the apertured tab 15 22, provides a very strong rigid and safe connection against wear and breakage through vibration or blows in use. The terminal connector described is of particular utility at all points and with all devices subject to great and continuous vibration, such as aeronautical motors, with which it may be used to overcome the prevailing and continuously occurring breaks at points where electrical conductors and cables are 20 25 detachably connected.

It is evident that various changes, modifications, variations and substitutions might be resorted to without departing from the spirit and scope of my invention, and hence 30 I do not wish to limit the invention to the exact disclosures hereof.

Desiring to protect my invention in the broadest manner legally possible, what I claim and desire to protect is:

35 1. In a terminal connector, pivotally mounted locking jaws in closed position swung together and abutting and each jaw formed with a recess in an abutting edge

portion thereof, the said recesses opposite each other, respectively, and in closed position of said jaws alined to form an opening therethrough adapted to receive a binding post, and cam surfaces formed at one side of said opening, whereby a binding post confined in said opening may swing said jaws to open position by pressure applied to force the post against said cam surfaces. 40 45

2. In a terminal connector, an engaging plate having an opening therethrough, locking jaws pivotally mounted on said plate, each of said jaws formed with a recess in the abutting edge portion thereof opposite each other respectively, and in closed position of the jaws forming an opening registering with the opening in said plate, projections on said jaws adapted to extend into the plate opening and engage the sides thereof to lock said jaws in closed position, and adjacent edge portions of said jaw recesses inclined toward said engaging plate 50 55 60 to form cam surfaces with the jaws in closed position.

3. In a terminal connector, an engaging plate having an opening therethrough to receive a binding post, locking jaws individually pivoted on said plate at the inner end thereof, each of said jaws formed with a recess in the abutting edge portion thereof opposite each other, respectively, and in closed position of the jaws forming an opening registering with the plate opening, and the adjacent edge portions of said recesses at the pivoted ends of said jaws formed to provide a surface inclined toward said plate with said jaws in closed position. 65 70

HARRY P. DAVIS.
